ABSTRACT: A carrier for the narrowing device of a flat knitting machine moves from a leading position to a trailing position on a carriage when the carrier is arrested while the carriage moves along a needle bed, and a cam arrangement on the carrier and carriage operates the narrowing during the carrier arrest. The arresting mechanism is triggered by a jack butt in the needle bed which tilts an actuating arm on the carriage by abutting engagement, the actuating arm pivoting a toothed stopping arm on the carrier into engagement with a toothed arresting rail on the needle bed.

FIG. 6

ARRESTING MECHANISM FOR A CARRIER MOUNTED
ON A CARRIAGE OF A FLAT KNITTING MACHINE

BACKGROUND OF THE INVENTION

This invention relates to flat knitting machines, and particularly to an arresting mechanism for arresting a carrier which is movable between a leading position and a trailing position on a carriage traveling back and forth along the needle bed during operation of the machine. The carrier moves between these positions relative to the carriage when arrested during movement of the carriage.

Such an arresting mechanism is needed on flat knitting machines equipped with a narrowing device which must stand still while transferring loops of yarns between knitting needles, and it is known to arrange the device on a carrier movably mounted on the knitting carriage or on a separate narrowing carriage coupled to the knitting carriage. The narrowing device must be arrested at a point of the carriage path which shifts as the width of the knitted fabric increases or decreases during knitting. When the narrowing operation is completed, the carrier of the narrowing device must be released so that it may continue its movement with the carriage.

In early arresting mechanisms, needle butts were used for stopping the carrier, but the relatively brittle needles tended to break under the impact of the carrier. It has therefore been proposed to arrange abutments for the carrier of the narrowing device on threaded spindles which extend along the length of the needle bed and are turned to adjust the arresting point. Such devices are relatively complex, therefore subject to failure in service and quite costly. Moreover, they interfere with access to the needle beds.

A primary object of this invention is the provision of a single and compact mechanism for arresting a carrier for a narrowing device in proper alignment with the needles in a needle bed of a flat knitting machine so that the ensuing relative motion of the knitting carriage and the arrested carrier may provide the motive power for the device mounted on the carrier.

SUMMARY OF THE INVENTION

With this object and others in view, as will hereinafter become apparent, the invention provides two engageable arresting members. The first arresting member is mounted on the needle bed directly or by means of the machine frame. The second arresting member is mounted on the carrier for movement toward and away from a position of engagement with the first arresting member. An actuating member is movably mounted on the carriage on which the carrier may move between a leading and a trailing position. The actuating member is mounted on the carriage in such a manner that it abuttingly engages a suitably positioned butt of a knitting implement on the needle bed, such as a needle or a jack, and is moved by the engaged butt from an inactive to an active position during the carriage movement.

A motion-transmitting train connects the actuating member to the aforementioned second arresting member and moves the latter into its position of engagement in response to movement of the actuating member into its active position. A cam on the carriage disengages the second from the first arresting member when the carrier reaches its trailing position, and thereby permits the trailing carrier to resume movement with the carriage.

Other features and many of the attendant advantages of this invention will readily become apparent from the following detailed description of a preferred embodiment when considered in connection with the appended drawing.

BRIEF DESCRIPTION OF THE DRAWING

FIG. 1 shows an arresting mechanism of the invention and associated elements of an otherwise conventional flat knitting machine in side elevational section on the line I-I in FIG. 2;

FIG. 2 illustrates the apparatus of FIG. 1 in fragmentary view at right angles to the plane of a needle bed shown in FIG. 1 but not itself visible in FIG. 2;

FIG. 3 shows jacks of the knitting machine and an associated cam in a perspective view;

FIGS. 4 to 6 show the device of FIG. 2 in sequential positions during movement of the knitting carriage.

5 DESCRIPTION OF THE PREFERRED EMBODIMENT

The drawing shows only as much of an otherwise conventional flat knitting machine as is needed for an understanding of this invention which resides mainly in the arresting mechanism. While this mechanism will be discussed hereinafter in its use for a narrowing device, that device itself, as far as not specifically illustrated and described, is not a part of this invention and may also be conventional, for example, as disclosed in German Pat. No. 653,734, issued to Sadami Imon on Dec. 3, 1937.

Referring initially to FIG. 1, there is seen one of the two guide rails 1 of the knitting machine frame on which a non-illustrated knitting carriage and a partly illustrated narrowing carriage 24 travel when coupled to each other in a known manner. A carrier box 22 is movably mounted on the carriage 24 and normally travels with the same. When the box is stopped while the narrowing carriage moves on the rails 1, narrowing implements 35 carried by the box 22 are operated in a manner not directly relevant to this invention by non-illustrated cams and cam followers on the box 22 and the carriage 24. As shown in FIG. 2, the box is in its leading position on the carriage 24.

The narrowing implements 35 transfer yarn loops between knitting needles 4' in a needle bed 4. The needles are backed in the needle bed 4' by lifting jacks 5 having respective butts generally indicated by the numeral 6. The knitting needles are in the active or operating position when lifted by jacks 5 whose butts stand in a row 7. When a needle is retracted to an inactive or inoperative position, the butt 6 of the associated jack 5 stands in a lower row 8. The jack 5 fully visible in FIG. 1 is positioned to hold the associated latch needle in an intermediate or ready position, and its butt 6 stands on a level 9 between the rows 7, 8.

The jacks 5 on the intermediate level 9 cooperate with an axial projection 12 on an actuating arm 11 pivotally mounted on a supporting plate 10 which is a fixed element of the carriage 24. The plate 10 is parallel to the row of needles 4', the arm 11 is mounted on the face of the plate 10 remote from the needle bed 4, and the projection 12 extends through an opening of the plate toward the jacks 5.

Before knitting starts, as many jacks 5 are raised manually to the active position as the width of the fabric to be knitted may require. As is better seen in FIG. 3, a hook 32 projects from the bottom end of each jack 5 into a recess 33 in a longitudinal edge of an adjacent jack directly above the hook 32 of the latter. The length of the recess is such as to limit the longitudinal spacing of two adjacent jacks to the distance between the butt levels 7 and 9 or to the distance between the levels 9 and 8. The last jack raised to the active position on either selvage end of a fabric knitted on the needle bed 4 thus causes the butt of the next outer jack to be raised to the intermediate level 9. The jacks positioned nearer the end of the needle bed 4 are in the active position. A backing cam 13 on the supporting plate 10 has the shape of a double wedge dimensioned and positioned to move between the row 7 of active jack butts and the ready jack butt 9 with minimal clearance.

One end of a shaft 17 journaled in the carrier box 22 fixedly carries a radial arm 16 adjacent the plate 10, and the other end of the shaft carries a stopping or arresting arm 18 equipped with teeth 23. The teeth are spaced and shaped for conforming engagement with saw teeth on an arresting rail 2 fixedly mounted on the guide rail 1. The spacing of the teeth on the rail 2 corresponds to one needle spacing in the needle bed 4. The arm 18 is provided with an axially projecting pin 20 whose function will presently become apparent together with 70 that of a control bar 25 which is fixedly mounted on a portion

of the carriage 24 which has been omitted from the drawing for the sake of clarity.

As is shown in FIG. 2, the knitting machine is equipped with an additional arresting rail 3 attached to the stationary guide rail 1. The rails 2,3 respectively extend from the center of the rail 1 toward the two ends of the latter, and their saw teeth are oppositely inclined. The needle bed 4 has been omitted from the showing of FIG. 2 together with the jacks 5 for the sake of clarity, but FIG. 2 shows the row 7 of jack butts associated with operative needles, the row 8 of jack butts associated with inactive needles, and the single butt 9 associated with a needle in the intermediate or ready position.

The free end of the arm 11 has a circularly arcuate cam face 15, and the arm is biased counterclockwise into the inactive position shown in FIG. 2, by a helical tension spring 14 attached to the plate 10. A helical tension spring 19 attached to the carrier box 22 and to the hammer-shaped arm 18 biases the latter, the shaft 17, and the arm 16 in a clockwise direction, as viewed in FIG. 2, for engagement of a rounded cam face 21 on the arm 18 with the control bar 25 which has an enlarged portion between two obliquely inclined cam faces 26.

The teeth 23 on the arm 18 are inclined for locking engagement with the teeth of the rail 2, but cannot effectively engage the teeth of the rail 3. An additional shaft 30 is journaled in the box 22 and its two ends respectively carry arms 28,29 which are mirror images of the aforescribed arms 16,18, but are axially offset in a manner not explicitly shown to prevent interference with the arm 18 and associated elements. Teeth 23a on the arm 29 are inclined for locking engagement with the teeth of the rail 3. A cam 27 is mounted on the portion of the carriage 24 not seen in FIG. 1 for engagement with the projecting pins 20 on the arm 18 during relative movement of the carrier box 22 and the carriage 24 longitudinally of the needle bed 4.

The aforescribed apparatus operates as follows:

As is seen in FIGS. 2, 5 and 6, the spring 14 normally swings the arm 11 upward until the top face of the projection 12 abuts against the fixed, wedge-shaped backing cam 13. Obliquely inclined cam faces on the front and rear ends of the projection 12 cooperate with corresponding cam faces of the cam 13 to lead the butt 9 into a gap which is opened between the projection 12 and the cam 13 by the entry of the butt as the box 22 moves with the carriage 24 in the direction of the arrow from the position shown in FIG. 2 into that illustrated in FIG. 4. The arm 16 which is held in engagement with the cam face 15 of the arm 11 is pivoted counterclockwise against the restraint of the spring 19 when the butt 9 is received between the projection 12 and the cam 13, and its teeth 23 lock the carrier box 22 to the stationary frame of the knitting machine by engagement with the teeth of the rail 2, as shown in FIG. 4. The carriage 24 with the elements fixedly mounted thereon continues its movement along the needle bed 4 together with the nonillustrated knitting carriage and the knitting cams mounted on the latter.

The arresting arm 18 remains locked to the rail 2 after the projection 12 and the cam 13 have moved with the carriage 24 beyond the butt 9, and the spring 14 has again drawn the actuating arm 11 from its active position into the inactive position adjacent the cam 13 (FIG. 5). The saw teeth 23 on the stopping arm 18 are not readily dislodged from the mating teeth of the rail 2 as long as friction between the carrier box 22 and the carriage 24 tends to drive the teeth into each other. Moreover, the control bar 25 engages the cam face 21 of the arm 18 and prevents accidental disengagement from the rail 2.

As the cam face 21 reaches the trailing, obliquely inclined cam face 26 of the control bar 25 during continued movement of the carriage 24 relative to the stopped carrier box 22, the cam 27 engages the projecting pin 20 on the stopping arm 18, and lifts the teeth 23 sufficiently from the teeth of the rail 2 to permit the arm 18 to be returned to its initial position by the spring 19, as is shown in FIG. 6, which illustrates the carrier box 22 in its trailing position on the carriage 24.

The transfer of loops between needles 4 is performed by the implements 35 during the movement of the box 22 between the leading and trailing positions respectively illustrated in FIGS. 2 and 6. The carriage and control box thereafter travel 5 jointly with the nonillustrated knitting carriage, and the procedure described above is repeated at the other selvage of the knitted fabric when the box 22 is again in a leading position relative to the narrowing carriage 24 after reversal of carriage movement. The box is stopped during the return movement of the carriage by the teeth 23a on the arm 29 engaging teeth on the rail 3 when the arm is swung clockwise from the position shown in FIGS. 2, 4, 5, and 6 by a nonillustrated actuating lever and motion-transmitting elements corresponding to those described with reference to the movement of the arm 18.

A cam 31 illustrated in FIG. 3 only and mounted on the plate 10 in a manner not further illustrated shifts the butt 9 into the row 8 after the narrowing operation, whereby the last butt from the row 7 is pulled into position 9 by engagement of 15 a hook 32 with a recess 33 as described above.

While the invention has been described with reference to a knitting machine in which the narrowing implements are mounted on a separate carriage capable of being coupled to the knitting carriage proper as may be needed, the invention is 20 equally applicable to other arrangements in which narrowing implements are arranged on a carrier analogous to the box 22 and mounted on the knitting carriage itself for movement between leading and trailing positions on the carriage as the latter is moved back and forth by the nonillustrated machine drive along the needle bed 4.

It is normally preferred to rely on jack butts for actuating the arresting mechanism of this invention, but it is evident that the nature of the butt-carrying knitting implements employed 25 is not directly relevant to this invention. Needle butts may be utilized in an analogous manner.

The butts do not absorb the full impact of the carrier which is being arrested, but mainly cause pivotal displacement of the actuating lever 11, a motion which is transmitted to the arresting arm 18 by the cam face 15 on the lever 11, the arm 16, and the shaft 17. The arresting arm 18 transmits only a minor portion of the forces of impact during arrest of the carrier box 22 to the butt 9 while the butt is being backed by the cam 13, and thus protected from damage.

The arresting mechanism of the invention is relatively simple and consists of sturdy parts capable of long useful life. It occupies little space and does not obstruct access to the needle beds nor to other elements of the knitting machine which require relatively frequent inspection and maintenance.

I claim:

1. In a flat knitting machine having a frame (1), a needle bed (4) on said frame, a carriage (24) movable back and forth on said frame along said needle bed, a multiplicity of knitting elements (4a, 5) spacedly juxtaposed in said needle bed in the direction of carriage movement and having respective butts (6), the implements being movable in said needle bed transversely of said direction toward and away from a ready position (9) of the associated butts, a carrier (22) movable on said carriage in said direction between a leading position and a trailing position, a device (35) on said carrier operated in response to movement of said carrier between said positions of the same, and an arresting mechanism for arresting said carrier while in said leading position during movement of said carriage until the carrier is shifted from said leading position to said trailing position, the improvement in the arresting mechanism which comprises:
  - a. a first arresting member (2) on said frame (1);
  - b. a second arresting member (18) mounted on said carrier (22) for movement toward and away from a position of engagement with said first arresting member;
  - c. an actuating member (11) mounted on said carriage (24) for abutting engagement with one of said butts (9) in said ready position, and for movement by the engaged butt from an inactive to an active position during said carriage movement;

- d. motion-transmitting means (15,16,17) connecting said actuating member to said second arresting member for moving the latter into said position of engagement in response to the movement of said actuating member into said active position; and
- e. cam means (27) on said carriage for moving said second arresting member away from said position of engagement when said carrier reaches said trailing position thereof.
2. In a machine as set forth in claim 1, said first arresting member being a toothed rail, the spacing of the teeth on said rail corresponding to the spacing of said knitting implements, and said second arresting member carrying teeth (23) matingly engaging the teeth of said rail in said position of engagement.
3. In a machine as set forth in claim 1, said implements including a plurality of knitting needles (4a) and a plurality of jacks (5), said needles and jacks being elongated, and each jack carrying one of said butts and being longitudinally juxtaposed to a respective knitting needle.
4. In a machine as set forth in claim 1, said second arresting member and said actuating member being respectively pivotally mounted on said carrier and said carriage.
5. In a machine as set forth in claim 1, backing means (13) on said carriage for preventing movement of the associated knitting implement (5) transverse to said direction when said one butt (9) in the ready position is abuttingly engaged by said actuating member.
6. In a machine as set forth in claim 5, yieldably resilient means (14) biasing said actuating member from said active toward said inactive position, and control means (25) mounted on said carriage (24) for retaining said second arresting member in said position of engagement after movement of said actuating member from said active toward said inactive position, and for releasing said second arresting member when said carrier (22) approaches said trailing position.
